CLAIM

I claim the ornamental design for a hinged electrical junction box, as shown and described.

DESCRIPTION

FIG. 1 is a perspective front side view of a first embodiment of the hinged electrical junction box with tabs in a closed position;

FIG. 2 is a top elevational view of the design shown in FIG. 1;

FIG. 3 is a front elevational view of the design shown in FIG. 1;

FIG. 4 is a rear elevational view of the design shown in FIG. 1;

FIG. 5 is a right-side elevational view of the design shown in FIG. 1;

FIG. 6 is a left-side elevational view of the design shown in FIG. 1;

FIG. 7 is a bottom elevational view of the design shown in FIG. 1;

FIG. 8 is a perspective view of the design shown in FIG. 1 with the tabs in an open position;

FIG. 9 is a perspective front view of a second embodiment of the hinged electrical junction box with the tabs in a closed position;

FIG. 10 is a top perspective view of the design shown in FIG. 9;

FIG. 11 is a front elevational view of the design shown in FIG. 9;

FIG. 12 is a rear elevational view of the design shown in FIG. 9;

FIG. 13 is a right-side elevational view of the design shown in FIG. 9;

FIG. 14 is a left-side elevational view of the design shown in FIG. 9;

FIG. 15 is a bottom elevational view of the design shown in FIG. 9; and,

FIG. 16 is a perspective view of the design shown in FIG. 9 with the tabs in an open position.

The broken lines shown in the figures represent portions of hinged electrical junction box that forms no part of the claimed design.
